HUMIDIFIER

Gerald W. Skilbeck, Kenosha, Wis.

Application December 11, 1933, Serial No. 701,812
Renewed December 11, 1935

7 Claims. (Cl. 237—78)

This invention relates to certain new and useful improvements in humidifiers and refers more particularly to humidifiers for use in homes, although the invention is readily applicable to commercial installations.

It is an object of this invention to provide simple and inexpensive means for automatically maintaining a predetermined degree of humidity.

Another object of this invention is to provide a humidifier having an evaporator element of novel construction adapted to hold water in such a manner that a large expanse thereof is constantly exposed for evaporation and having means controlled by the fluctuations in the weight of said element arising from the evaporation of water therefrom for maintaining a predetermined quantity of water in said element.

And a further object of this invention is to provide a humidifier which while readily applicable to a conventional sectional radiator and so constructed as to be substantially concealed between the sections thereof, is likewise susceptible to use with other types of radiators.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a rear view of a conventional hot water or steam radiator, illustrating the humidifier of this invention applied thereto;

Figure 2 is a detail sectional view through Figure 1 on the plane of the line 2—2;

Figure 3 is a perspective view of a portion of the humidifier; and

Figure 4 is an enlarged detail sectional view illustrating the valve for controlling the supply of water to the evaporating unit.

Referring now more particularly to the accompanying drawings in which like numerals indicate like parts throughout the several views, the numeral 5 designates a conventional hot water or steam radiator of the type for which the humidifier of this invention is particularly designed. The radiator 5 comprises similar con-

nected sections 6 and has an inlet 7 and an outlet 8.

The humidifier consists of a plurality of evaporator units 9 disposed between certain of the sections 6, and supplied with water by a duct 10, 5 having automatically controlled communication, to be hereinafter described, with each of the units 9. The entire structure is supported from a bar 11 clamped to the radiator by a plurality of screws 12.

The clamping screws 12 are threaded in angular brackets 13 welded or otherwise secured to the bar 11 and likewise attached to the supply duct 10. The headed ends of the screws pass through cross bars 14 which project into the 15 customary vertical slots 15 of the radiator sections to receive support therefrom.

Supported jointly by the bar 11 and the supply duct 10 is a plurality of spouts 16, one for each of the evaporator units 9. The closed end 20 portions of the spouts are communicated with the supply duct 10 through discharge ports 17 in the form of nozzles projecting above the lower wall of the spouts.

Arms 18 are pivotally mounted as at 19 within 25 the spouts. The free ends of the arms project outwardly of the open ends of the spouts to support the evaporator units, which are suspended from the free ends of the arms by links 20 attached to the evaporator units and having cross 30 heads 21 engaging the free ends of the arms as shown. Secured to the undersides of the arms adjacent their pivotal mountings are sealing strips 22 formed of rubber or other suitable material and adapted to engage the open ends of 35 the nozzles or ports communicating the spouts with the supply tube.

The arms are yieldably retained in raised positions holding their removable sealing members 22 off of the ports 17, by expansile springs 23 attached to the arms as at 24, and having their other ends anchored to adjustable supports 25 carried by the bar 11. The tension of the springs 23 is opposed by the weight of the evaporating units 9 suspended from the outer ends of the 45 arms so that when sufficient water has been supplied to the evaporator units, the arms are pulled down closing their ports 17 and shutting off the supply of water.

The adjustment of the supports 25 for the tension springs enables determination of the weight at which the valves close. Obviously, as the water evaporates from the units 9, they become lighter and the springs again open the ports admitting additional water. In this manner, the 55

fluctuations in the weight of the evaporator units due to evaporation of the water therefrom automatically maintains a predetermined quantity of water in the evaporator units.

5 The particular construction of the evaporator units is, of course, subject to modification and may be designed to accommodate any particular condition.

In the present instance, these units consist of 10 two sheets 26 of asbestos or similar absorbent material joined at their sides and bottom marginal edges by a metal frame 27. The frame members are channel shape in cross section so that the lower member provides a trough or 15 shallow reservoir.

The upper edges of the sheets 26 are bound 20 with metal strips 28, which as best illustrated in Figure 3, have their medial portions flattened to afford an enlarged entrance into the space between the two sheets to receive the water which 25 drips from the ends of the spouts. To insure alignment of the open upper ends of the units with the ends of the spouts, the links 20, which are non-rotatably connected with their supporting arms, are also non-rotatably secured to the units, preferably by rivets 29 passing through loops at the lower ends of the links.

From the foregoing description taken in connection with the accompanying drawings, it will 30 be readily apparent to those skilled in the art, that this invention affords an efficient and inexpensive humidifier which is readily applicable to a heating unit such as a hot water or steam radiator, and that it provides novel and extremely 35 simple means for determining and maintaining a predetermined degree of humidity.

What I claim as my invention is:

1. A humidifier adapted for use in conjunction 40 with a heating unit, comprising a flat element of absorbent material adapted to be disposed adjacent a portion of the heating unit and to be saturated with water, a channeled member arranged to drop water onto said element, a liquid discharge port to supply liquid to said member, a 45 pivoted arm lying within said channeled member and having means to close said port, a spring to yieldably hold the arm in its open position, and means to suspend said absorbent element from the arm so that fluctuations in the weight of the 50 absorbent element acts against said spring to pull the pivoted arm down into the channeled member to close the port whereby the weight of the absorbent element acting in conjunction with 55 said spring automatically controls the supply of water to said element.

2. A humidifier adapted for use with a heating unit, comprising a substantially flat element of absorbent material adapted to be disposed adjacent a portion of the heating unit, a water supply duct adapted to be fixed to the heating unit, a spout projecting from the duct with its discharge end arranged to drop water onto said element, a port between the water supply duct and said spout, a pivoted member disposed within said spout and having means to close said port, adjustable spring means to yieldably hold the pivoted member in its open position, and means to suspend the said element from the pivoted 70 member so that the weight of said element and the water held thereby acts against the spring means to pull the pivoted member down toward the bottom of the spout to close the port so that the weight of said element and the water held thereby acting in conjunction with the spring 75

means automatically controls the supply of water to said element.

3. A humidifier adapted for use in conjunction with a heating radiator, comprising an elongated water supply duct, supporting means for said duct adapted to be clamped to the radiator, a plurality of water discharge spouts extending laterally from said supply duct, all of said discharge spouts being communicated with said supply duct, a pivoted arm associated with each discharge spout and adapted when in a lowered position to close off communications between its discharge spout and the supply duct, adjustable spring means for each arm to yieldably retain the same in an elevated position permitting the 15 passage of water from the supply duct to the discharge spouts, and an evaporating unit suspended from the end of each arm to receive water dropping from the discharge spout, said evaporating units when saturated with water over-balancing the springs and pulling the arms down to 20 close off communication between the spouts and the supply duct whereby fluctuations in the weight of said evaporating units automatically controls the supply of water thereto. 25

4. A humidifier adapted for use in conjunction with a heating unit, a water supply duct, means to clamp the duct to the heating unit, a water discharge spout extending laterally from said supply duct, said discharge spout being communicated with the supply duct, a pivoted arm disposed longitudinally within said spout, means to pivotally mount said arm adjacent its connection with the supply duct so that its outer free end is movable vertically toward and from the 30 bottom of the spout, said arm having a part adapted when in its lowered position to close off communication between the spout and the supply duct, spring means to yieldably retain the arm in an elevated position permitting the 35 passage of water from the supply duct to the discharge spout, and an evaporating unit suspended from the free end of the arm to receive water dropping from the discharge spout, said evaporating unit being disposed adjacent part of the 40 heating unit and when saturated with water over-balancing the spring to pull the arm down into its position shutting off communication between the spout and the supply duct, whereby fluctuations in the weight of said evaporating unit 45 automatically control the supply of water thereto. 50

5. In a humidifier adapted for use in conjunction with a heating unit, an evaporating unit comprising two sheets of absorbent material face to face and sufficiently close together to cause 55 water dropped between the sheets to spread evenly over the entire surface of both sheets, and means to supply water to said evaporating unit to maintain the same saturated.

6. A humidifier of the character described comprising an evaporator unit composed of two sheets of absorbent material, means to hold said sheets of absorbent material in side by side relationship and sufficiently close together to cause 60 water dropped therebetween to spread evenly over the entire surface of both sheets, means at the upper end of the evaporator unit to guide water into the space between the sheets, and means to drop water onto said last named means. 65

7. In a humidifier of the character described, 70 an evaporator unit composed of two sheets of absorbent material, means to hold said sheets of absorbent material in face to face relationship and sufficiently close together to insure water dropped 75 therebetween to flow evenly over the entire sur-

face of both sheets, means at the upper edges of the sheets to provide a binding therefor and to guide water between the sheets, a movable arm from which the evaporating unit is suspended, spring means to hold the arm up against the weight of the evaporator unit, said spring means yielding to allow downward movement of the arm upon an increase in weight of the evaporator

unit effected by an increase in its water content beyond a predetermined degree, and a water supply controlled by the movements of the arm and adapted to drop water onto said means at the upper edges of the sheets comprising the evaporator unit. 5

GERALD W. SKILBECK.
